UNITED STATES PATENT OFFICE.

JOSEF PEJCHAR, OF NEW YORK, N. Y.

CUFF-BUTTON.

SPECIFICATION forming part of Letters Patent No. 758,101, dated April 26, 1904.

Application filed July 13, 1903. Serial No. 165,265. (No model.)

To all whom it may concern:

Be it known that I, JOSEF PEJCHAR, a citizen of Austria-Hungary, residing at New York city, Bronx, county of Westchester, State of New York, have invented certain new and useful Improvements in Cuff-Buttons, of which the following is a specification.

This invention relates to a cuff-button which is of simple construction, may be readily manipulated, and becomes securely attached to the cuff.

In the accompanying drawings, Figure 1 is a perspective view of a cuff provided with my improved button. Fig. 2 is a perspective view of the button; Fig. 3, a section through the cuff with the button inserted, and Fig. 4 a face view of a modification of the button.

The cuff-button is made from a single piece of metal or other rigid material. It is composed of two shanks α , that converge toward the front, where they merge into a central tapering horn α' . The horn is flanked by a pair of forwardly-projecting jaws α'' , which extend from the shanks α to a point beyond the apex of the horn. Between the horn and the jaws there are formed a pair of converging slots α'' , which merge into one another at the apex of the horn and are accessible through a common inlet α^4 , formed between the spaced converging ends of the jaws. Thus the two edges of the cuff are introduced into the common opening α^4 and are then spread to the right and left to be engaged by the right and left slot

α'' , respectively. The outer edges of the horn and the inner edges of the jaws are preferably 35 corrugated, so that the slots α'' are sinuous, and thus take a firm hold upon the cuff.

In use the shanks α are passed through the buttonholes A' of a cuff A , while the fabric in front of the buttonholes is grasped between 40 the horn α' and jaws α'' . In this way the button becomes firmly attached, while the buttonhole is covered and concealed by the rearwardly-extending shanks α .

In Fig. 4 the horn α' is perforated to economize weight, and the ends of the shanks α carry balls b , which constitute additional safeguards against accidental opening.

It will be seen that my improved cuff-button is hingeless, of simple construction, may 50 be readily manipulated, and effectively conceals the buttonholes from view.

What I claim is—

A cuff-button composed of a pair of converging shanks, a central horn, and a pair of 55 converging jaws that extend beyond the horn to form a pair of converging slots which merge into one another at the apex of the horn, and have a common inlet between the converging ends of the jaws, substantially as specified. 60

Signed by me at New York city, (Manhattan,) New York, this 11th day of July, 1903.

JOSEF PEJCHAR.
